FIG. 6.

UNITED STATES PATENT OFFICE.

MAX WENZEL, OF SPREMBERG, GERMANY.

MACHINE FOR PIECING TOGETHER THE THREADS OF WARPS.

1,133,830.

Specification of Letters Patent.

Patented Mar. 30, 1915.

Application filed December 17, 1912. Serial No. 737,232.

To all whom it may concern:

Be it known that I, MAX WENZEL, a citizen of the Empire of Germany, residing at No. 18 Mühlenstrasse, Spremberg, Kingdom of Prussia, Empire of Germany, have invented certain new and useful Improvement in Machines for Piecing Together the Threads of Warps, of which the following is a specification.

10 In the process and the apparatus according to the patent application S. N. 714446 and 714447 the piecing of the ends of warp lying side by side is operated by spinning or whipping, and this is done by means of 15 one single piecing tool. Also all other appliances known hitherto for piecing the ends of warp threads, as, for instance, warp thread attaching and warping appliances are possessed of only one single tool for operating the piecing of the threads. Consequently, in all known machines only the piecing of one pair of threads during one 20 operation of the machine is possible. Now, the number of operations of all these appliances during a certain unit of time is 25 limited by the fact that the speed of the secondary appliances for parting and feeding the threads to be pieced cannot exceed a certain rate. Besides, the maximum 30 speed of working depends upon the material to be worked, because, of course, threads of bad, easily breaking material cannot stand the same speed of working as threads of better material. It is therefore impossible 35 to surpass per hour a number of threads of as great as 6000 to 8000 with the machines and appliances known, even in straining their parts to the utmost by working them with the highest speed which is safe; and 40 only one machine working with a knotting tool has surpassed this number.

By arranging a number of whipping appliances side by side, each having to handle a pair of threads, an apparatus constructed 45 according to this invention is able to piece together a number of threads simultaneously at each stroke thereby increasing the output many times without increasing the number of strokes per unit of time, thus combining 50 maximum safety with maximum output. This capacity of enabling a number of piecing appliances to be arranged side by side differentiates the improved apparatus from all hitherto known devices for piecing warp 55 threads, such as twisting and tying devices, all of which comprise only one piecing ap-

pliance, so that only one piecing can be effected at each stroke.

The drawings illustrate a form of apparatus comprising a number of whipping 60 appliances for piecing together a number of pairs of threads at each stroke of the apparatus.

In these drawings: Figure 1 is a perspective diagrammatic general view of the co-operating devices, Fig. 2 being a plan, Fig. 3 a rear elevation, and Fig. 4 a side elevation thereof, Figs. 5, 6, 7 and 8 illustrate details of the device employed for separating and conveying the ends of the threads 70 to be pieced, and gripping and severing the same.

In the apparatus comprising several whipping appliances (Figs. 1 to 8) the whipping appliances *e* (Figs. 1, 3, 4, 6) have the form 75 of disks with teeth 2 and radial insertion slots 3 for the threads. In each whipping appliance one separate thread is used for whipping around the warps, which thread is fed to the appliance in the same manner 80 as described in applicant's Patent 1,098,308. In the example shown, three such whipping appliances are arranged side by side. They are mounted so as to be capable of rotary movement but not of axial sliding 85 movement in a plate-shaped carrier 4 which is movable parallel to itself along the warp threads. The plate-shaped carrier 4 slides on fixed guide bars 5, 6 that are fixed to the sides 7, 8 of the framing. The carrier 4 90 of the whipping appliances *e* receives its parallel motion along the warp threads as above stated for the purpose of carrying the whipping thread in some path or other to-and-fro along the warp threads. The path 95 chosen in the example shown in the drawings, is indicated at D in Fig. 3. Since at each operation of the machine the carrier 4 of the whipping appliances is required to make a movement only during the actual 100 whipping process, the said movement may be produced by means of a suitable shaped cam 9 on a cross shaft 10 which is driven in the ration 1:1 from the main shaft 11 (Figs. 3 and 4) of the machine. This shaft 105 11 makes one complete revolution for each complete operation of the machine and is driven for instance by an electric motor 12 (Fig. 3) through a worm 13 and worm wheel 14. This worm wheel is not fixed 110 directly on the main shaft 11 but is loose thereon and is connected thereto by a clutch

15 slidable along the shaft 11. This clutch has a breaking cone 16 which engages a fixed female cone 17 when the clutch 15 is moved into engagement by electromagnetic or mechanical means by the thread stop motion devices when the check thread is absent as hereinafter described.

On the shaft 10 there are preferably provided two cams 9 each of which acts upon a lever 19 in opposition to a spring 18. The levers 19 have a common rocking axle 21 and the free ends of their arms are connected together by a cross bar 22 attached to a link 20 the other end of which engages 15 a fork 23 fixed on the carrier 4 of the whipping appliances.

The whipping appliances e receive their rotary motion in common from the main shaft 11 of the machine. On this shaft is 20 a toothed wheel 24 (Fig. 4) the teeth of which extend over only $\frac{2}{3}$ rds of its circumference, which is adapted to engage a smaller intermediate wheel 25 on an intermediate shaft 26. On this latter shaft is a 25 spur wheel 27 with broad teeth engaged by a spur wheel 28 on the carrier 4. The teeth of the wheel 27 are sufficiently broad to prevent the wheels 27 and 28 from coming out of engagement during the parallel 30 motion of the carrier (Fig. 2). The wheel 28 engages the ring of teeth 2 of the whipping appliance e^1 and also a small intermediate wheel 29 which transmits its motion to the driving wheel 28' of the whipping 35 appliance e^2 and engages a second small intermediate wheel 29' which in its turn engages the driving wheel 28'' of the whipping appliance e^3 . The direct transmission of the rotary motion from one whipping 40 appliance to the other is necessary because the whipping appliances when stationary must always have their insertion slots 3 coinciding with the respective insertion slots 3' in their carrier 4. Vertically below and 45 parallel to the axis of rotation of the middle whipping appliance e^2 there is arranged so as to be rotatable but axially immovable in fixed bearings a shaft 30 which carries opposite to each other two rings of teeth 31, 32 the tooth spaces of which receive each one end of a warp thread in such a manner that corresponding spaces contain those warp threads which are to be pieced. For the purpose of facilitating the introduction 50 of the warp threads in the plane of the warp and preventing their removal from the tooth spaces during the piecing operation, pairs of guide wires 33, 34, are arranged directly adjacent to the rings of teeth 31, 32 and preferably on both sides thereof. These wires are fixed to the sides 55 7 and 8 of the framing. The shaft 30 is caused to rotate step by step by a ratchet mechanism the ratchet wheel 35 (Fig. 4) of 60 which is fixed on the shaft while the pawl 65

36 rotates together with the spring pawl 37 loosely on the shaft 30. The pawl 36 is connected by means of a connecting rod 38 to a slide 40 guided vertically in a guide 39 on the outside of the frame wall 8. This slide 70 is moved downward in opposition to an upwardly pressing spring 41 by a tappet 42 on a shaft 43 parallel to the main shaft. According as the rings of teeth 31, 32 are to be advanced only one tooth or a number 75 of teeth, the shaft 43 is rotated in the corresponding ratio by means of spur wheels 44, 45 from the main shaft 11. As the pitch of the teeth 31, 32 corresponds to the distance of the whipping appliances e from 80 one another, the pairs of warp threads to be pieced are brought by the teeth 31, 32 each time into the correct position below the insertion slots 3, 3' (Fig. 4). The warp threads can then be raised in pairs in the 85 manner well known in twisting machines out of the plane of the warp into the whipping appliances. It is however necessary first to effect a complete separation of the threads from one another over their entire 90 length between the rims of teeth 31, 32 so that later on only those ends of the warp threads which belong to each other shall lie close to each other. For this purpose a separating device is provided the separators 95 of which are moved along the warp threads after each separator has engaged only one warp thread. The separators consist of grippers of forks 46 arranged on common carriers 47, 47' and fixed to endless bands 100 or chains 48, 48' which are mounted on guide rollers 49, 50, 51 and 49', 50', 51'. The carriers 47, 47' of the separators 46 have guide arms 52, 52' which are adapted to slide in guides 53, 53' fixed to the frame sides 7, 8 (Fig. 4). These separators 46 also serve to secure the parallel position of the warp threads relatively to one another so that they can be securely grasped by the grippers or tongs which convey the warp 105 threads into the whipping appliances. 110

The endless belts 48, 48' with the separators are driven from the main shaft 11 (Figs. 2, 3, 4) by means of bevel wheels 54, 55, cross shaft 56, bevel wheels 57, 58, vertical shaft 59, bevel wheels 60, 61 and cross shaft 62. On the latter shaft is a spur wheel 63 gearing with a spur wheel 64 on the extended axle 65 of the guide roller 49'. On the extended axle 65 is a second spur wheel 66 gearing with an intermediate wheel 67 on a pin 68 parallel to the axle 65, which wheel gears with a spur wheel 69 on the extended axle 70 of the guide roller 51. The ratio must be such that a group of separators will execute their complete operation at each operation of the machine. The separated warp threads a and b which have been separated and arranged parallel and close together in pairs are now gripped by 120 125 130

gripping devices, cut away from their holding clamps K and K' and inserted into the insertion slots of the whipping appliances. The separation of the warps and the clamping thereof in the desired position in clamps K, K' is also effected in the manner described in Patent 1,098,308. The clamps in that patent corresponding to the clamps K, K' of the present application are numbered 120 and 121. One of these gripping devices with severing devices is shown in Figs. 6, 7, 8. The grippers for all the pairs of threads are connected together by a common cross piece 71, 71' which is guided by means of vertical guide bars 73, 73' in guides 72, 72' which are fixed together with the guides 5 and 6 of the carrier 4 of the whipping appliances to the frame sides 7, 8. The upper ends of the guide bars 73, 73' carry pins or rollers 74, 74' by means of which they engage in cam grooves 75, 75' of cams fixed on a common shaft 76. The shaft 76 is driven from the main shaft 11 in the ratio of 1:1 by means of spur wheels 77, 78 (Figs. 2, 3, 4). The gripping devices consist of forks each having three prongs 79, 80, 81. The two side prongs 79 and 81 are bent outward while the middle prong is wider and is formed on one side with a cutting edge (Fig. 8). Parallel to the plane of the prongs there is pivoted on a pin 82 on the fork a hook 83 the shank of which carries a spring clamping jaw 84 which coöperates with a clamping jaw 85 fixed on the fork behind the middle prong 80. To the hook 83 there is fixed a small tooth segment 86 gearing with a toothed segment 87 which is pivoted on a pin 88 on the fork. The segments 87 are under the influence of springs 89 which have a tendency to turn the segments in such a manner as to cause the hook 83 to assume the open position shown in full lines in Fig. 7.

The segments 87 of each group of grippers are connected together by a connecting rod 90 one end of which is connected to a lever 91 whose pivot 92 is fixed on one of the outer forks of the group. In the descent of the gripping devices the lever 91 strikes with its free end against a fixed stop which moves it into the position shown in dotted lines in (Fig. 7). In this movement a spring pawl 93 drops over the lever 91 or a projection thereof so that this lever retains the position shown in dotted lines in Fig. 7 during the following ascent of the gripping devices.

In the movement of the lever 91 from the drawn out position into the dotted position shown in Fig. 7 all the segments 87 make a corresponding rotation which causes the hooks 83 to pass from the drawn out position shown in Fig. 7 into the dotted position. By this means the gap between the prongs 79, 80 of the forks is closed by the

hook and the warp thread that has entered this gap is shut in by the hook, while the other warp thread is clamped by the spring jaw 84 on the shank of the hook 83 and the fixed jaw 85 and the end of this thread is severed behind the clamping point by the cutting edge on the middle prong 80. This severing action can be improved by providing a counter cutting edge (Fig. 8) on the shank of the hook 83 which moves close above the middle prong 80. After the threads *a* and *b* have been taken up and severed alternately in this manner the gripping devices are moved up by the cams 75, 75'. These cams are formed so that the raised position will be maintained so long as is necessary for the following whipping operation. On the next downward movement of the gripping devices the lever 93 must be disengaged in order that the ends of the warp threads which are held by the grippers shall be released and the grippers shall assume a position ready for receiving the next warp thread ends. For this purpose at the commencement of the downward movement a pivoted spring shoulder 94 on the pawl 93 strikes a fixed stop 95 which the pivoted part 94 was able to avoid in the upward movement and is disengaged so that the springs 89 can act and return the grippers into the position shown in full lines in Fig. 7.

For the purpose of returning the whipping appliances always and exactly with the insertion slots 3' of their carrier, when the whipping operation is completed, there are provided braking and locking devices which in engaging the teeth 24 of the driving wheel of the main shaft 11, are disengaged and engaged when the teeth 24 leave the wheel 25.

The several threads are taken singly out of the lease by means of suckers 96 (Fig. 5). For each lease there is provided a pair of suckers of which each works on one side of the lease. The mouths of the suckers are of trough shape. These troughs extend along the warp threads which are to be taken by the respective sucker from the lease. The mouths of the suckers which operate in the middle of the lease are arranged transversely to the warp threads which are not to be taken by the said sucker and they force back the threads which are not yet pieced. In front of the suction aperture which is recessed in the mouth-piece, a spring locking pin 97 is passed transversely through the mouthpiece. This locking pin is mounted on the arm 98 of a bell crank lever 98, 100, pivoted on a pin 99 on the sucker 96. The arm 100 of this lever is forced back by a fixed stop 101 when the sucker is in its position of taking up, in such a manner that the locking pin 97 leaves the mouth-piece aperture for the entry of the thread 130

unobstructed. Immediately the sucker leaves its taking up position, the arm 100 leaves the fixed stop 101 and it is forced by its spring 102 into the locking position.

5 In order that the locking pin 97 shall release the thread after the latter has entered the corresponding toothed space of the ring of teeth, a bell crank lever pivoted on an upwardly directed bracket 143 on the sucker 10 strikes with its arm 144 against a correspondingly fixed stop 146 while the arm 145 of the bell crank lever acts upon the arm 100 of the locking pin lever with a tendency to raise the locking pin 97. Normally the 15 bell crank lever 144, 145 is forced with its arm 144 by a spring 147 against the stop 148 on the bracket 143 whereby the bell crank lever is secured in its rest position.

In order to impart to the sucker the necessary motion for conveying the taken up thread into the gap of the corresponding ring of teeth, the sucker 96 which is formed as a tube, is pivoted by means of a cock pluglike pin 103 on the lower end of a hollow arm 104, the eye 105 of which receiving the pin 103 is constructed in the form of a cock casing. The bores of the eye 105 and of the plug like pin 103 are so arranged and dimensioned that their complete openings 25 will coincide with each other when the sucker is in its taking up position (Fig. 5 left hand side). On the upper end of the hollow arm 103 there is also formed an eye 106 having the shape of a cock casing rotatable on a hollow pin 107 which is fixed and from the bore of which there extends a side aperture coinciding with the bore 108 of the eye 106 in the taking up position of the sucker 96. The hollow pin 107 is fixed to a 30 suction pipe. The arrangement is such that the current of the suction is controlled by the movements of the sucker 96 and the arm 104 so that the suction will be operated only in the taking up position of the sucker. 35 The arm 104 is fixed to an inclined arm 109 engaged by a crank rod 110 which engages at its other end a crank pin 111 on a crank shaft 43 that is parallel to the main shaft 11. The shaft 43 is driven from the main 40 shaft 11 by means of toothed wheels 44, 45 in the ratio of 3:2, two pairs of suckers being provided which operate alternately and together have to deliver three pairs of threads for each operation of the machine. 45 50 In addition to their to-and-fro motion the suckers must also have an up and down motion because they must be moved out of the path of the delivered warp thread when they are in position for delivering the thread. For this purpose rocking links 115 having a variable longitudinal elasticity are provided which are adapted to rock on a common pin 116 and are pivoted at their lower ends to the suckers 96. At their 55 upper ends the links 115 have a lateral guide

pin 117 which moves in a guide curve 119 which is closed upon itself and is provided with a spring switch tongue 118.

For the purpose of checking the groups of threads, each xth thread of the lease is 70 preferably passed at each side of the lease over a separate rod 120 (Fig. 1) so that it is situated on a higher level outside the lease than the other threads. In this higher position the check thread C is able to act 75 upon the stop lever 121, 122 of which the lower arm 121 carries at its end a shoe 123 arranged across the length of the warp. The stop lever is pivoted on a fixed pin 124 and the free end of its upper end 122 projects into the path of the contact piece 126 arranged on a stop disk 125 so that by means of the stop lever 122 and the contact piece 126 an electrical circuit can be closed containing a source of current and the stopping 80 electromagnet E (Fig. 2). The stop disk 125 is moved onward by ratchet mechanism 127 to 134 the number of the step by step movements corresponding to the number of the threads comprised in one stop group. The ratchet wheel of the stop disk can have 85 only a determined number of teeth. It is however not always possible to make the number of threads in the check groups equal in all warps. Therefore means must be 90 provided to enable the number of step by step movements of the stop disk 125 to be varied according to the varying number of threads in the check groups. This can be 95 done without difficulty by arranging the 100 stop disk 125 so as to be capable of being rotated forward and backward and providing it with two oppositely working ratchet mechanisms whose ratchet wheels have the same number of teeth. It is then merely 105 necessary to provide an automatic reversing of the two ratchet mechanisms and to arrange on the stop disk in addition to the 110 contact piece 126 a removable contact piece 126' which is fixed by the contact piece 126 on the stop disk 125 in accordance with the 115 number of step by step movements or pitch corresponding to the number of threads. The drawings (Figs. 1, 2, 3) show a construction of a checking apparatus of this kind. 127 and 128 are the two oppositely 120 acting ratchet wheels which are fixed on the shaft 129 of the stop disk 125 and in which pawls 130, 131 are adapted to engage. Both these pawls are fixed to a lever 132 125 and are pivoted on a common pin 133 which is fixed to a ratchet lever 134. To the latter is connected a connecting rod 135 which receives to-and-fro motion from a cam 136 on the transverse shaft 56. The pawls 130, 131 are reversed according to the desired 130 direction of rotation of the stop disk 125 by means of two reversing levers 137, 138, pivoted on a common shaft 112 parallel to the shaft 129. Each reversing lever has a 135

locking arc 149 and 149' respectively fixed to it into which a spring 153 or 153' acting upon a bell-crank lever 151, 152 or 151', 152' has a tendency to force a locking pin 5 150 or 150' which is mounted on the arm 151 or 151' of the bell-crank lever (Figs. 1 and 3). The locking mechanism serves to hold each reversing lever in opposition to the action of a spring 113, 114 on its 10 other and upwardly directed arm 137' or 138' in the position shown in Figs. 1, 3 and 4. The levers are released by means of removable pins 154, 154' provided on the stop disk 125, as soon as the one or the other 15 contact piece 126 or 126' has moved into the contact position, so that one or the other pin 154, 154' acts upon the corresponding releasing lever 151, 152 or 151', 152'. The spring 113 or 114 then imparts to the respective reversing lever a rotation such that 20 it will rotate the common arm 132 of the pawl 130, 131 into the other position and thus cause the other pawl to engage with its ratchet wheel. The stop disk will then 25 be rotated in the reverse direction. The immediate returning of the corresponding reversing lever after reversal is effected by means of side pins 155, 155' of a slide 156 which receives a continuous to-and-fro motion 30 through a connecting rod 157 and crank 158 from a shaft 159 which is driven from the shaft 56 in the ratio of 1:3, so that the slide is moved to-and-fro once at every double stroke of the pawl. The pins 155, 155' 35 act upon the upwardly directed arms 137' and 138' of the reversing levers 137, 138. On reaching the position of rest the locking pin 150 or 150' enters again into the locking arc 149 or 149'. The closing of the 40 circuit effected by the checking apparatus energizes the electro-magnet E (Fig. 2) the armature 140 of which is movable in opposition to a spring 139 and serves as a support for a weighted lever 141 which on 45 being released swings down and by means of the disengaging lever 142 fixed to it shifts the clutch part 15 on the main shaft 11 in such a manner that the coupling of the shaft 11 with the worm wheel 14 is 50 opened and the brake cone 16 is driven into the fixed female cone 17 whereby the main shaft 11 is disconnected and stopped immediately.

The operation as a whole of the apparatus 55 is as follows:—The warp threads of the two warps that it is desired to be pieced together which are to be fed simultaneously to the whipping appliances *e* are taken up singly by the suckers 96, 97 and transferred upon 60 the successive gaps of the stepwise rotating toothed rims 31, 32 from which they are brought finally under the slot shaped opening in the whipping appliance *e*. At the same time the separating means 46, 47, fixed

to the endless bands 48, 48', moving in opposite direction, separate the threads and place them in parallel position. Now the warp threads which lie exactly parallel the one next to each other and in a straight line, are each taken up by one of the whipping 65 appliances to which a separate whipping thread is fed as described in Patent 1,098,308 and the whipping takes place in the same manner as described in that patent except that here it takes place simultaneously in the three whipping appliances. The finished threads are then fed farther by the toothed rims 31, 32. If one of the controlled threads *C* should miss, the two warps so far as the controlled threads are 70 concerned will not agree so that when the machine proceeds wrong threads of both warps will be pieced and in such case the stopping mechanism will enter into operation by the dropping of the lever on 121. The 75 machine is stopped thereby and the mistake can be corrected at once before as might have happened before, a number of the wrong threads of both warps have been pieced together which had afterward to be 80 separated again.

What I claim is:

1. In a machine of the kind described for piecing together the ends of warp threads, a number of whipping appliances arranged 95 side by side and means for simultaneously conveying a pair of threads to each whipping appliance, essentially as described and for the purpose set forth.

2. In a machine of the kind described for 100 piecing warp threads, the combination of a plurality of whipping appliances arranged side by side and each provided with an inserting slot; means for guiding thereto the ends of the warp thread to be pieced; co- 105 axially arranged toothed rings one for each set of warp threads, the pitch between the teeth thereof being equal to the required width between the threads to be pieced, each ring being adapted to receive in the gap between adjacent teeth one thread to be pieced; and means for rotating said rings step-by-step.

3. In a machine of the kind described for piecing warp threads, the combination of 115 a plurality of whipping appliances arranged side by side and each provided with an inserting slot; means for guiding thereto the ends of the warp thread to be pieced; co- 120 axially arranged toothed rings one for each set of warp threads, the pitch between the teeth thereof being equal to the required width between the threads to be pieced, each ring being adapted to receive in the gap between adjacent teeth one thread to be 125 pieced; means for rotating said rings step-by-step; means for separating the warp threads in said gap over the entire length

and holding the separated threads in the right position for insertion into the whipping appliances for subsequent whipping.

4. In a machine of the kind described for piecing warp threads, the combination of a plurality of whipping appliances arranged side by side and each provided with an inserting slot; means for guiding thereto the ends of the warp thread to be pieced; coaxially arranged toothed rings one for each set of warp threads, the pitch between the teeth thereof being equal to the required width between the threads to be pieced, each ring being adapted to receive in the gap between adjacent teeth one thread to be pieced; means for rotating said rings step-by-step; separators to hold the warp threads between the toothed rings over the entire length and for holding the warp threads in the right position for inserting into the whipping appliances, said separators being mounted between said rings for movement along the warp threads; and means for moving the separators in the same direction along the warp threads.

5. In a machine of the kind described for piecing together the ends of warp threads, a number of whipping appliances arranged side by side; means for simultaneously conveying one pair of thread ends to each whipping appliance; one pair of lease rods each for each warp end; one spaced lease rod for each αth thread of each warp end, which special lease rod is located higher than the corresponding lease rods; a contact lever in whose path the threads running over the higher special lease rod are located; a stop disk (125); a contact (126) mounted on the said stop disk; means for rotating the stop disk with the contact piece in proportion to the feeding of the thread and a stop circuit which may be closed by the contact lever and the contact piece (126) when one of the check threads guided over the higher lease rods is missing, essentially as described and for the purpose set forth.

6. In a machine of the kind described for piecing together the ends of warp threads, a number of whipping devices arranged side by side; means for simultaneously conveying one pair of thread ends of each whipping appliance; one pair of lease rods each for each warp end; one special lease rod for each tenth thread of each warp end, which special lease rod is located higher than the corresponding lease rods; a contact lever in the path of which the threads running over the higher special lease rod are located; a stop disk; a contact mounted on said stop disk; means for rotating the stop disk with the contact piece in proportion to the feeding of the thread; a stop circuit which may be closed by the contact lever and the contact piece when one of the check threads guided

over the higher lease rod is missing; a removable contact piece (126') mounted upon the stop disk; two ratchets operating in opposite direction which can be made to cooperate alternately with the stop disk reversible pawls mounted upon said ratchets and means for reversing these pawls in order to reverse the motion of the stop disk when either the fixed or the movable contact piece have reached the contact position, essentially as described and for the purpose set forth.

7. In a machine of the kind described for piecing together the ends of warp threads, a number of whipping appliances arranged side by side; means for simultaneously conveying one pair of thread ends to each whipping appliance; means for holding in position both the warp ends that have to be pieced together; one pair of lease rods for each warp end for producing leases; two suckers each for each lease to draw out the single thread ends; means for making the suckers operate alternately to the right and to the left in the corresponding leases at the place where the threads cross each other; and mouth pieces for the suckers which serve for pushing away in the leases the threads which should not be drawn out, essentially as described and for the purpose set forth.

8. In a machine of the kind described for piecing together the ends of warp threads, a number of whipping appliances arranged side by side; means for simultaneously conveying one pair of thread ends to each whipping appliance; means for holding in position both the warp ends that have to be pieced together; one pair of lease rods for each warp end to produce leases in the warp ends; two suckers each for each lease to draw out the single thread ends from the lease; means for making the suckers operate alternately to the right and to the left in the corresponding lease at the place where the threads cross each other; mouth pieces for the suckers; grooves in these mouth pieces running in the direction of the thread which is to be drawn out of the lease and suction openings in said mouth pieces located deep in the grooves, essentially as described and for the purpose set forth.

9. In a machine of the kind described for piecing together the ends of warp threads, a number of whipping appliances arranged side by side; means for simultaneously conveying one pair of thread ends to each whipping appliance; means for holding in position both the warp ends that have to be pieced together; one pair of lease rods for each warp end for producing leases in the warp ends; two suckers each for each lease to draw out the single thread ends from the lease; means for making the suckers oper-

- ate alternately to the right and to the left in the corresponding lease at the place where the threads cross each other; mouth pieces for the suckers; grooves in these mouth 5 pieces running in the direction of the thread which is to be drawn out of the lease; suction openings in said mouth pieces located deep in the grooves; automatic locking devices for holding the suckered thread in the 10 mouth piece of the sucker; means for moving the suckers from the leases to the whipping appliance and vice versa; and means for cutting off the suction current from the suckers during the motion of the latter from 15 the leases to the whipping appliance, essentially as described and for the purpose set forth.
10. In a machine of the kind described for piecing together the ends of warp threads, 20 a number of whipping appliances arranged side by side; means for simultaneously conveying one pair of thread ends to each whipping appliance; means for holding in position both the warp ends that have to be 25 pieced; one pair of lease rods for each warp
- end to produce leases in the warp ends; two suckers each for each lease, to draw out the single thread ends from the lease; means for making the suckers operate alternately to the right and to the left in the corresponding lease at the place where the threads cross each other; mouth pieces for the suckers; grooves in these mouth pieces running in the direction of the thread which has to be drawn out of the lease; suction openings 30 in said mouth pieces located deep in the grooves; automatic locking devices for holding the suckered thread in the mouth piece of the sucker; means for moving the suckers from the leases to the whipping appliances and vice versa; hollow rods in the sucker joints in these hollow rods and cock shaped joint pins in the joints, essentially as described and for the purpose set forth.
15. In testimony whereof I affix my signature 40 in presence of two witnesses.

MAX WENZEL.

Witnesses:

GEORGE A. MAKINSON,
PAUL WALTHER.
